United States Patent Office

Des. 182,420
Patented Apr. 1, 1958

182,420

SERVING TRAY

Michael S. Lax, New York, N. Y., assignor to Kromex
Corporation, Cleveland, Ohio, a corporation of Ohio

Application March 13, 1957, Serial No. 45,239

Term of patent 14 years

(Cl. D44—10)

I claim:

The ornamental design for a serving tray, substantially as shown.
